US0D1064466S

(12) **United States Design Patent** (10) **Patent No.:** **US D1,064,466 S**
(45) **Date of Patent:** **** Feb. 25, 2025**

(54) **POOL CLEANER**

(71) Applicant: **Compurobot Technology Company**,
Dongguan (CN)

(72) Inventor: **Wing-tak Hui, Kwun Tong (HK)**

(73) Assignee: **Compurobot Technology Company**,
Dongguan (CN)

(**) Term: **15 Years**

(21) Appl. No.: **29/884,612**

(22) Filed: **Feb. 14, 2023**

(51) LOC (15) Cl. **15-05**

(52) U.S. Cl.

USPC **D32/21**

(57) **CLAIM**

The ornamental design for a pool cleaner as shown and described.

DESCRIPTION

FIG. 1 is an elevated side perspective view of a pool cleaner, showing my new design;

FIG. 2 is a front view thereof;

FIG. 3 is a rear view thereof;

FIG. 4 is a right-side view thereof;

FIG. 5 is a left side view thereof;

FIG. 6 is a top view thereof; and,

FIG. 7 is a bottom view thereof.

The broken lines in the drawings depict portions of the pool cleaner that forms no part of the claimed design.

1 Claim, 7 Drawing Sheets
